Inventor:

Hermann C. Priebe,

Hermann C. Priebe

UNITED STATES PATENT OFFICE.

HERMAN C. PRIEBE, OF BLUE ISLAND, ILLINOIS.

CAR-UNDERFRAME.

No. 870,130.

Specification of Letters Patent.

Patented Nov. 5, 1907.

Application filed April 13, 1907. Serial No. 368,036.

To all whom it may concern:

Be it known that I, HERMAN C. PRIEBE, a citizen of the United States, residing at Blue Island, county of Cook, and State of Illinois, have invented certain new and useful Improvements in Car-Underframes, of which the following, taken in connection with the drawing, is a description.

My invention has for its object the production of an underframe and body bolster for cars, and is designed 10 to simplify the construction and strengthen certain parts of the underframe particularly those parts subjected to the buffing and pulling strain.

With these and other objects in view the present invention consists in the combination and arrangement 15 of parts as will be hereinafter more fully explained, shown in the drawings and pointed out in the claims, it being understood that changes in form, proportion, size and minor details may be made within the scope of the claims, without departing from the spirit of or sacrificing any of the advantages of the invention and in the 20 drawings.

Figure 1 is a cross section of the car sills, and illustrating a side elevation of the body bolster; Fig. 2 is a 25 top plan view thereof. Fig. 3 is a detail of a modification.

In carrying out my invention A represents the floor of the car, B the longitudinal sills and C the center sill which is arranged with the flat side thereof against the car floor as shown.

30 D is the body bolster which is constructed of two separate pieces or sections and secured at each side thereof to the sills B, B. The inner end B', B' of each section of the bolster is extended upwardly between the center sill C and the longitudinal sill at the side thereof. 35 Channel irons c, c are arranged upon each side of the longitudinal center sill and a bolt c' extends through the longitudinal sill C, channels c, c and the parts B', B' of the bolster. Said channel irons are also riveted to the sides of the upright portions of the bolster at c², c². A 40 filler block E is provided beneath the center sill and between the two halves of the bolster and has the upright parts B', B' of the bolster and the channels c, c secured thereto by bolts or rivets. e is the king bolt which extends through the filler block E. A channel 45 e' is arranged between the longitudinal center sill and the filler block E and is riveted or bolted to the sides of the channels c, c as shown.

Extending from the top of the longitudinal center sill C and the parts B', B' of the bolster is a reinforcing 50 or strengthening plate E' which is bent at a downward angle at each end thereof to conform to the side of the sill B and B, and again at right angles to extend beneath said sills and between said sills and the bolster and is secured to said bolster at e², e² and to the bolsters

and sills at e³, e³. The two sections of the bolster D, D, 55 are secured at the outer end thereof to the outer sills B, B, by the bolts b, b. Each section of the bolster D, D, is braced between the bottom and the upright portions thereof by the braces d, d.

In Fig. 3 I have shown a modification of the center 60 sill construction to be used in case it is desired to employ double sills instead of one as shown in Fig. 1. In this instance two center sills f, f, are used and the channels c, c are bolted thereto by the bolts f' and the channel iron e' is disposed beneath said sills and secured 65 to the channels c, c, as shown. The bolster sections are then secured in position the same as illustrated in Fig. 1.

I claim:

1. In a car underframe, the combination of a car floor and sills, with a bolster comprising two sections secured to said sills, each of said sections having an upright portion extending between the center and intermediate sills, and channel irons between the bolster sections substantially as described. 70

2. In a car underframe, the combination of the car floor and sills with a body bolster comprising two sections, each of said sections having an upright portion which extends between the center and intermediate sills, channel irons between the center sill and bolster sections and a 80 filler block between said bolster sections.

3. In a car underframe the combination of the car floor and longitudinal sills, the side of the center sill being against the car floor, with a bolster comprising two separate sections, each of said sections having an upright portion fitting between the center sill and the next side sill, channel irons between the center sill and the upright portions of the bolster sections, and means for securing said bolster sections, channel irons and center sill together, substantially as described. 85

4. In a car underframe, the combination of the car floor and longitudinal sills, the side of the center sill being against the car floor, with a bolster comprising two separate sections, each of said sections having an upright portion fitting between the center and intermediate sills, 95 channel irons between the center sill and the upright portions of the bolster sections, and a filler block beneath the center sill and between the bolster sections.

5. In a car underframe, the combination of the car floor and longitudinal sills, with a bolster having two 100 separate sections, each of said sections having an upright portion fitting between the center sill and the next sill thereto, channel irons secured to the center sill and the upright portions of the bolster sections, a filler block, a channel iron between said filler block and the center sill, 105 and means for securing the aforesaid channel irons together, substantially as described.

6. In a car underframe, the combination of a car floor and the longitudinal sills, with a bolster having two separate sections, each of said sections having an upright portion extending between the center sill and the sill next to it, channel irons between said center sill and upright portions of the bolster sections, a filler block between said sections, and a reinforcing plate extending above the longitudinal sills and the upright portions of the bolster sections and secured to the longitudinal sills. 115

7. In a car underframe, the combination of the car

door and sills, with a bolster comprising two sections, each of said sections having an upright portion fitting between the longitudinal sills, a center sill, channel irons between the center sill and bolster sections and a reinforcing plate above the center sill and upright portions of the bolster sections.

8. In a car underframe, the combination of the car floor, side sills and double center sills, with a body bolster comprising two separate sections, each of said sections

having an upright portion fitting between one of said center sills and the sill next to it, and channel irons reinforcing said center sills, substantially as described.

In testimony whereof, I have signed this specification in the presence of two subscribing witnesses.

HERMAN C. PRIEBE.
